Patented November 1, 1904.

UNITED STATES PATENT OFFICE.

ANDREW J. SANFORD, OF NEWARK, OHIO, ASSIGNOR TO A. H. HEISEY & CO.,
OF NEWARK, OHIO.

DESIGN FOR A GLASS BOWL.

SPECIFICATION forming part of Design No. 37,203, dated November 1, 1904.

Application filed September 26, 1904. Serial No. 226,054. Term of patent 7 years

To all whom it may concern:

Be it known that I, ANDREW J. SANFORD, a citizen of the United States, residing at Newark, in the county of Licking and State of Ohio, have invented a new, original, and ornamental Design for a Glass Bowl, of which the following is a specification, reference being had to the accompanying drawing, forming part thereof.

10 The figure is a side view of a bowl, showing my new design.

What I claim as new, and desire to secure by Letters Patent, is—

The ornamental design for a glass bowl, as shown.

ANDREW J. SANFORD.
